US00D755415S

(12) **United States Design Patent**
Taylor(10) **Patent No.:** **US D755,415 S**
(45) **Date of Patent:** **** May 3, 2016**(54) **LED LAMP**

- (71) Applicant: **TADD, LLC**, Cary, IL (US)
- (72) Inventor: **Timothy Taylor**, Barrington, IL (US)
- (73) Assignee: **TADD, LLC**, Cary, IL (US)
- (**) Term: **14 Years**
- (21) Appl. No.: **29/519,210**

(22) Filed: **Mar. 3, 2015**(51) **LOC (10) Cl.** **26-04**(52) **U.S. Cl.** **USPC D26/2**

(58) **Field of Classification Search**
USPC D26/1-4, 113, 118; 313/313, 315, 316,

High Power E27 60 LED light LED Bulb light lamp 220V 3W;
<http://www.lovesaction.com>.*Primary Examiner* — Ian Simmons*Assistant Examiner* — Harold Blackwell, II(74) *Attorney, Agent, or Firm* — Clark Hill PLC; James R. Foley(57) **CLAIM**

The ornamental design for an LED lamp, as shown and described.

DESCRIPTION

FIG. 1 is a perspective view of the LED lamp;

FIG. 2 is a side view thereof;

FIG. 3 is a top view thereof; and,

FIG. 4 is a bottom view thereof.

The broken lines illustrate portions of the LED lamp which form no part of the claimed design.
